UNITED STATES PATENT OFFICE.

WILLIAM READING GULICK, OF JERSEY CITY, NEW JERSEY.

PROCESS OF MAKING A STABLE VOLATILE COMPOSITION SUITABLE FOR EXPLOSIVE-ENGINES.

1,187,061.

Specification of Letters Patent. Patented June 13, 1916.

Application filed July 31, 1913. Serial No. 782,292.

To all whom it may concern:

Be it known that I, WILLIAM R. GULICK, a citizen of the United States, residing at Jersey City, county of Hudson, State of New Jersey, have invented certain new and useful Improvements in Processes of Making a Stable Volatile Composition Suitable for Explosive-Engines, of which the following is a specification.

10 The object of this invention is to produce a compound which can be used as a substitute for gasoline in explosive engines and which like gasoline can be ignited in such engines by an electric spark.

15 In carrying out the invention I have discovered a process of making a stable volatile composition from crude petroleum or its non-volatile liquid by-products such as kerosene and distillates, the composition being 20 susceptible to ignition by an electric spark. The compound, while volatile, may be termed stable because it is uniform and homogeneous throughout the entire volume and will maintain these characteristics indefinitely 25 when allowed to stand and is not affected by temperature variations of the weather. In other words, the ingredients of the compound have entered into combination and will not separate or change by lapse of time 30 or changes in weather conditions.

I am aware that others have suggested various means in the effort to make use of crude petroleum and its non-volatile constituents in explosive engines, and that some 35 have endeavored to use a mixture containing such ingredients with gasoline, and it is a well known fact that none of the workers in this art heretofore has produced a compound from such ingredients which can be used in 40 an ordinary carbureter of an explosive engine and ignited by an electric spark or a composition which would be stable, maintaining its characteristics on standing. My composition is distinguished from any of 45 these previous experiments by the fact that it is a stable compound and not a mere temporary mixture, and can be used at any ordinary temperatures exactly like gasoline in an ordinary carbureter to produce an explosive 50 mixture in the cylinder of an engine which will be ignited by an electric spark. I have found that such a compound will not be made by simply mixing gasoline with crude oil or its non-volatile liquid by-products, but that the elements must be brought

together in the way which I have discovered in order to bring about the proper combination. I have discovered that the compound can be produced by bringing the gasoline and non-volatile liquid constituents of crude 60 petroleum together in such a way that one of them will be practically atomized and the atoms will thus be brought into intimate association with the atoms of the other ingredients. The material which is in a closed 65 chamber to prevent evaporation is then stirred or agitated in any suitable way for several hours, and thereafter the material is allowed to stand for some hours, the result being that the gasoline will combine 70 with the other material and will thoroughly dissolve or consume the elements of grease, oil, paraffin or other greasy or fatty matter that may be in the material. There is thus a union between the ingredients and they will 75 not separate or deteriorate by lapse of time. As a specific illustration of my process I place a certain amount of gasoline in a closed chamber which I term a converter and I supply crude petroleum or its non- 80 volatile liquid by-products under pressure to the upper part of the chamber, spraying it through an atomizing nozzle against the inner wall of the chamber allowing the atomized particles to come in contact with the vapor above the gasoline and to fall on the gasoline itself in the finely divided and separated particles. While the material is being thus supplied the gasoline is agitated 85 by any suitable means and this is continued for about two hours so that there is a thorough commingling and intimate association of all parts of the material. The material is then allowed to stand for about two hours or longer so as to bring about a more thorough 90 dissolution of the fatty carbonates. I have found that the proportion of gasoline and crude oil or its constituents can vary within rather wide limits and that the limits 95 of the variation depend on the character of the non-volatile elements which are used. I have successfully used as low as 25% gasoline in producing such compound capable of use in explosive engines, as above described, and of ignition by electric sparks.

In producing my fuel and in carrying out my process I may make use of any suitable apparatus and the present invention is of course not limited to any particular machine for that purpose.

In the drawing, the single figure shows a device partly in section which may be used in carrying out the process.

In this drawing, 1 represents a chamber or converter of any suitable size or shape which may be closed and which is adapted to contain a certain volume of gasolene 2 in the bottom thereof. A pipe 3 leads into the upper part of the chamber and discharges against the inner side wall and it will be understood that crude petroleum or its non-volatile liquid by-products are to be supplied through this pipe under pressure so that it will be reduced to a very fine spray or atomized against the wall of the chamber. It will be understood that there is some vapor in the chamber arising from the surface of the gasolene and the atomized non-volatile elements will be intimately mixed with this vapor and will descend to the surface of the liquid gasolene entering into it. A shaft 4 is shown extending vertically within the chamber and having arms 5 extending therefrom for the purpose of agitating the gasolene and the fluid formed by the addition of the non-volatile constituents of the crude petroleum. The shaft may be rotated by any suitable means so as to agitate the material, the pulley 6 being shown for that purpose. The agitation of the material is carried on at the same time that the non-volatile material is supplied in an atomizing spray and after a sufficient quantity of the non-volatile material has been supplied, the agitation is continued for about two hours so as to keep the particles in intimate contact so that the chemical union between them can be completed. At the end of this stirring operation, the compound is allowed to stand for two hours or more whereby on account of the intimate association of the parts the elements of grease, oil, paraffin or other greasy or fatty matter that may be in the crude petroleum will be dissolved and the result will be a stable homogeneous solution. It should be noted that this is strictly a dissolution process and not one of distillation.

As compared with ordinary gasolene my improved composition can be manufactured at less cost and produces more power. It also possesses lubricating properties which can be relied upon to lubricate the cylinders of explosive engines and its use therefore effects a considerable saving in the cost of lubricating oil, as the chief item of expense for oil in connection with this class of engines is for lubricating the cylinders.

It is well known that when ordinary gasolene is used the cylinders of an explosive engine gradually become incrusted with what is known as "hard carbon", which carbon is very difficult to remove. One of the solvents commonly used for hard carbon is kerosene. My improved compound includes

a certain percentage of crude oil and I have discovered that it does not produce "hard" carbon in the engine cylinders. Such carbon as is produced is soft and flaky and it becomes loose and is blown out through the exhaust before it accumulates to an objectionable degree. I attribute the fact that hard carbon is not produced to the presence of a sufficient proportion of the kerosene element of crude oil in my new compound to constantly act as a solvent for any carbon that is produced in the cylinders of an engine and thus keep the same in a soft and flaky condition.

As crude petroleum and its non-volatile elements such as kerosene and distillates are cheaper than gasolene it will be evident that my improved composition can be produced at a lower price per gallon than gasolene. From numerous and continued tests, I have demonstrated that more power can be developed and greater mileage obtained from the new composition than from an equal quantity of ordinary gasolene, the increase in power and mileage being from 10% to 25%. The improved composition is adapted for use in ordinary marine, stationary and motor vehicle engines, of the internal combustion type, without any special adaptation of the carburetors or ignition devices. It is especially economical and desirable on account of its lubricating properties and it may be relied upon to keep the pistons thoroughly lubricated without recourse to ordinary lubricating oil, which latter is much more expensive. In this connection, the use of my new fluid renders impossible the sticking of pistons and other serious accidents which occasionally occur from neglect to provide ample supply of lubricant. While my composition produces more heat units and more power than the same volume of gasolene, I find that it does not heat the engine so much and that the same precautions for cooling the engine when in operation are not necessary. This is probably due to the lubricating effect of the composition.

I am aware that lubricating oil in small quantities, from 2 to 3%, has been used in gasolene for the purpose of lubricating the pistons of explosive engines, but such oil is not what may be termed a fuel oil and it detracts from the power which is developed by the engine rather than adding to it.

One of the advantages of my invention is that my new compound can be used not only as a substitute for gasolene but can be used with gasolene. In other words, my compound and gasolene can be placed in the same tank and the resulting fluid can be used just like gasolene in the operation of a motor of the internal combustion type. This gives to my compound a peculiar advantage for the reason that if the operator is using

my compound and is unable to secure an additional supply he may simply add gasolene to his tank and in the same way if he is using gasolene and my compound is accessible he may simply add it to his gasolene and continue to run his motor as before.

Having thus described the invention, what is claimed is:

1. The process of making a volatile compound from the non-volatile liquid constituents of crude petroleum and gasolene which consists in bringing the materials together by spraying one of the materials in such way that all particles of one will be brought 10 into intimate contact with the particles of the other throughout the material, agitating the material for several hours, whereby there will be a combination between the elements and allowing the compound to stand 15 until the union becomes complete and the fatty and greasy matter therein is dissolved forming a stable compound capable of use in an explosive motor and of ignition by an electric spark.
2. The process of making a volatile compound from gasolene and the non-volatile liquid constituents of crude petroleum which consists in spraying one of said materials 20 in contact with a body of the other material thereby bringing the particles into

intimate contact agitating the mass of material to assist the combination between the particles and allowing the composition to stand until the union between the particles has been completed and a stable volatile 35 compound is formed.

3. The process of making a volatile compound which consists in injecting the non-volatile liquid constituents of crude petroleum into a closed chamber containing gasolene, the said material being introduced in the form of an atomizing spray whereby there will be an intimate association of all particles, agitating the resulting material, during the supply of said non-volatile constituents and for about two hours, then allowing the compound to stand for several hours until the fatty and greasy matter therein and similar ingredients are thoroughly dissolved by the gasolene and until 40 there is a complete union of the particles of the two ingredients into a new compound which may be used in an explosive motor 45 and ignited by an electric spark.

In testimony whereof I affix my signature 50 in presence of two witnesses.

WILLIAM READING GULICK.
